CLAIM

The ornamental design for a star-shaped cheering stick, as shown and described.

DESCRIPTION

FIG. 1 is a perspective view showing my new design for a star-shaped cheering stick.

FIG. 2 is an elevation view thereof.

FIG. 3 is an elevation view rotated 90 degrees from FIG. 2.

FIG. 4 is a top plan view thereof; and,

FIG. 5 is a bottom plan view thereof.

The broken lines are included for the purpose of illustrating the portions of the star shaped cheering stick that form no part of the claimed design.

1 Claim, 3 Drawing Sheets
